United States Patent Office

Des. 221,879

Patented Sept. 14, 1971

221,879

MODEL RACING CAR

Daniel S. Gurney, Santa Ana, Calif., assignor to
All American Racers, Inc., Santa Ana, Calif.

Filed Sept. 10, 1970, Ser. No. 24,941

Term of patent 7 years

Int. Cl. D21—01

U.S. Cl. D34—15

FIG. 3

FIG. 4

FIG. 1 is a top plan view of the model racing car showing my new design;

FIG. 2 is a front elevational view thereof;

FIG. 3 is a left side elevational view, the right side being substantially a mirror image thereof; and

FIG. 4 is a rear elevational view thereof.

I claim:

The ornamental design for a model racing car, as shown and described.
